UNITED STATES PATENT OFFICE.

SAMUEL P. BUSH, OF COLUMBUS, OHIO, ASSIGNOR TO THE BUCKEYE STEEL CASTINGS COMPANY, OF COLUMBUS, OHIO.

CAR-COUPING.

1,132,434.

Specification of Letters Patent. Patented Mar. 16, 1915.

Application filed January 17, 1914. Serial No. 812,783.

To all whom it may concern:

Be it known that I, SAMUEL P. BUSH, of Columbus, in the county of Franklin and State of Ohio, have invented certain new 5 and useful Improvements in Car-Couplings; and I do hereby declare the following to be a full, clear, and exact description of the invention, such as will enable others skilled in the art to which it appertains to make 10 and use the same.

My invention relates to an improvement in car couplings, the object being to provide improved means for moving the locking block from its lock set position during the 15 opening movement of the knuckle, so that, after the knuckle has been thrown to open position, the locking block will be supported by the tail of the knuckle until the latter has closed sufficiently to permit the locking block 20 to drop from the same into locking position.

With this object in view my invention consists in the details of construction as will be more fully described and pointed out in the claims.

25 In the accompanying drawings, Figure 1 is a view in transverse vertical section of a coupling head showing the locking block in its lock set position and the knuckle closed; Fig. 2 is a similar view showing the knuckle 30 partly open and the weight of the locking block transferred from the lock set shoulder in the throat of the coupling onto the tail of the knuckle; Fig. 3 is a similar view showing 35 the position of the several parts, after the knuckle has been opened and partially closed, and Fig. 4 is a similar view showing the knuckle nearly closed, and the locking block supported on the extreme edge of the knuckle tail.

40 1 represents the coupling head and 2 the knuckle pivoted thereto in the ordinary manner, the side or edge 3 of the tail of the knuckle being straight and flat so as to have a maximum area of contact with the locking 45 block when the knuckle is closed.

The locking block 4 rests and moves within a housing in the head 1 of the coupling, and is supported and sustained against the pressure of the knuckle when under pulling 50 stresses, by the rear and side walls 5 and 6, and when in its lowered or locking position, it is supported at its lower end, at its four sides by the walls of the pockets 7, which as shown depend below the floor of the coupling head. This pocket and the walls of

the coupling head forms the housing for the locking block, in which the latter rests and moves, and which sustains it in position to operate automatically, after it has been lock set, or to be operated by lifting means either 60 at the bottom or top in the well known manner.

The outer side wall 6 of the housing for the locking block 4, is provided with the beveled seat 8; extending in the direction 65 of the length of the coupling so that the shocks due to impact and pulling, will be in the direction of the length of the seat. This seat is adapted to be engaged by the beveled shoulder 9, formed near the lower edge of 70 the locking block 4, and supports the latter in its lock set position, in which position the reduced portion 4^a of the block rests in the horizontal path of the movement of the knuckle, thus permitting the latter to turn 75 to its open position.

The locking block 4 is provided with a shoulder 4^b which in the present instance extends the width of the block, and the portion of the block below the shoulder is reduced in thickness, thus forming the reduced portion 4^a previously referred to. When the locking block 4 is in its lock set position this shoulder 4^b rests in a plane slightly above 80 the top surface of the adjacent edge of the 85 knuckle tail, so as to permit the knuckle to turn to open position.

When the knuckle and the locking block are in closed positions, the enlarged upper portion of the block 4 rests in the path of 90 movement of the tail of the knuckle and locks the latter in its closed position.

The tail of the knuckle is provided on its upper face with a tripping surface 2^a, the forward edge, or the edge toward the locking block 4, being inclined as shown at 2^b. This tripping surface 2^a may be provided with an incline abrupt or gradual at its rear end or face, or it may continue back straight 95 with no incline at all. The front edge of 100 this tripping surface is set back from the front or outer edge of the tail of the knuckle a distance sufficient to allow some movement of the knuckle without dislodging the locking block, and the shoulder 4^b on the block 105 is preferably provided at its end adjacent the knuckle, with a depending projecting surface 4^c, located wholly to one side of the center of gravity of the locking block. This depending surface 4^c is at the end of the 110

shoulder adjacent the knuckle and is wholly to the left of the center of gravity of the lock and is designed to make contact with the tripping surface 2^a on the upper face of 5 the knuckle tail, during the opening movement of the latter. This surface 4^a on the shoulder of the locking block need not be a projection, as the same result would follow if the shoulder 4^b were straight from end to 10 end, but by providing a projection having a rounded or angular surface, the locking block will be more sensitive and tilt more readily as soon as its weight is transferred to the tripping surface 2^a on the knuckle, 15 tail. The one essential point is that the surface of the shoulder on the locking block that is engaged by the tripping surface on the tail of the knuckle, shall lie to one side of the center of gravity of the locking block, 20 so that as soon as the block is lifted by the tripping surface, it will tilt in a direction to carry its shoulder 9 away from, and out of the vertical plane of the seat 8.

The coupling head is provided interiorly, 25 at a point above the knuckle with a rib 10, one face of which is substantially parallel fore and aft, with the side wall 6 of the coupling head, and of such distance therefrom, that, the upper end of the locking 30 block 4, may have slight sidewise or transverse movement between said rib and side wall so as to permit the block 4 to tilt.

When the block 4 is in its lock set position, as shown in Fig. 1, the preponderance 35 of weight of the upper end of the block is to the left, or toward the knuckle tail, hence when the block is lock set, its upper end rests against and is supported by rib 10. When so supported, the shoulder 4^b of the 40 block is in a plane slightly above the adjacent edge of the knuckle tail, but not above the plane of the tripping surface 2^a of the knuckle tail, hence the knuckle is free to be thrown to open position. Just 45 after it starts in its opening movement, its tripping surface 2^a coming in contact with the shoulder 4^b, lifts the block bodily and as this engagement is at the left of the center of gravity, the preponderance of weight 50 causes the upper part of the lock to rock to the right, thus carrying its shoulder 9 away from the seat 8, and the upper portion of the block over into contact with the side wall 6, and this position is maintained during 55 the entire opening movement. In the closing movement of the knuckle, the drag or friction between the tripping surface of the knuckle tail, and the locking block, shifts the latter bodily to the left and into 60 contact with the rib 6, as shown in Fig. 3, and thus holds the shoulder 9 out of the plane of the seat, and after the tripping surface of the knuckle leaves the shoulder 9, in closing, the block settles down on the 65 knuckle tail and carries its shoulder 9 in a

plane below the seat 8 as shown in Fig. 4, thus, absolutely preventing contact between these parts.

It will therefore be seen that with this improvement the locking block is dislodged 70 from its seat during the opening movement of the knuckle and is held suspended by tripping surface 2^a on knuckle tail and held away from its seat during the opening movement by gravity, and during the clos- 75 80 85 90 95 100 105 110 115 120 125 130

ing movement is pulled away from its seat by the drag or friction on the block, assisted by gravity. This construction possesses all the advantages of a lock set at the side and in the direction of the length of the coupling, so that the impact in pulling and pushing will be parallel to the seat of the lock set. The locking block may be actuated from the top by a chain, but I prefer to have the top closed to prevent the entrance of water and foreign substances, and actuate the block from below by a lifting lever similar to those now in use for that purpose.

It is evident that many slight changes might be resorted to in the relative arrangement of parts shown and described without departing from the spirit and scope of my invention. Hence I would have it understood that I do not wish to confine myself to the exact construction and arrangement of parts shown and described, but

Having fully described my invention what I claim as new and desire to secure by Letters-Patent, is:—

1. In a car coupling, the combination of a 100 coupling head the side wall of which is provided with a seat for supporting the locking block in its lock set position, a locking block having a shoulder to engage said seat and a shoulder the under face of which is adapted 105 to be engaged by the knuckle tail, the said latter shoulder being at one side of the center of gravity of the locking block, and a knuckle the tail of which is provided with a surface for lifting the locking block from its lock set seat and for supporting it while it turns by gravity to a vertical position away from said lock set seat during the opening movement of the knuckle, the said locking block being retained on the tail of 110 the knuckle during the closing movement of the knuckle by the drag or friction between the parts and by gravity.

2. In a car coupling, the combination of a 120 coupling head the side wall of which is provided with a seat for supporting the locking block in its lock set position, a locking block having a shoulder to engage said seat and a shoulder the under face of which is adapted 125 to be engaged by the knuckle tail, the said latter shoulder being at one side of the center of gravity of the locking block, and a knuckle the tail of which has an inclined surface whereby when the said inclined surface moves under its shoulder on the locking 130

block during the opening movement of the knuckle, the said block will be lifted from its lock set seat and tilt by gravity away from said lock set seat, and will be retained on the tail of the knuckle during the closing movement of the latter by the drag or friction between the parts and by gravity.

In testimony whereof, I have signed this specification in the presence of two subscribing witnesses.

SAMUEL P. BUSH.
